UNITED STATES PATENT OFFICE.

ANTHONY P. HINSKY, OF BROOKLYN, NEW YORK.

RADIO TRANSFORMER.

Application filed July 6, 1925. Serial No. 41,747.

This invention relates to a radio transformer. An object of the invention is to provide a simple and efficient transformer which is an improvement on the well known 5 spherical type of coil.

Another object is to provide a simple and efficient construction which is economical to manufacture and assemble.

The invention is illustrated in the drawings, of which—

Figure 1 is a perspective view; and

Figure 2 is a vertical section on the line 2—2 of Figure 1.

The form of the invention shown in the drawings is a preferred form, although it is understood that modifications in the construction and arrangement of the parts and in the character of the materials used may be adapted without departing from the spirit 20 of the invention as set forth in the appended claims.

In its general aspect the invention comprises a substantially spherical coil having open ends into which suitable insulating 25 plugs are disposed and to which plugs suitable bracket plates are connected to support the coil. Preferably wound around the great circle periphery of the spherical coil, in a plane at right angles to the axis of the basket ball, is a primary, which is a woven ringlike coil separately wound but disposed, as mentioned, and preferably tied to the periphery of the coil in any desired manner.

In the form of the invention shown in the drawings, I use a substantially spherical coil 10 having open ends at 11 and 12 into which fit, preferably, insulating plugs 13 and 14, to which plugs are connected bracket plates 15 and 16 acting as supporting members.

Preferably, separately wound but in the assembly disposed on the spherical coil 10 is a ringlike woven primary 17 which is suitably tied to the basket-ball coil or secondary in any desired manner. This primary is 45 preferably disposed around a great circle

periphery of the spherical coil, preferably in a plane at right angles to the axis of the coil running through the center of the plugs 13 and 14. Suitable connections such as 18 and 19 are led out from the primary; and connections 20 and 21, from the secondary.

This transformer is found to be highly efficient, has a minimum loss, and is exceedingly simple and economical to manufacture. The construction as described requires a 55 minimum amount of supporting material, thereby reducing losses.

What I claim is:—

1. A transformer, which comprises a spherical coil acting as a secondary, and a 60 ringlike woven primary disposed around a great circle periphery of the secondary.

2. A transformer comprising a substantially spherical shaped coil acting as a secondary, and a single ring-like woven primary coil associated with the secondary coil and disposed in a plane passing through the maximum diameter of the secondary coil.

3. A transformer, which comprises a spherical secondary coil having open ends, 70 insulating plugs disposed in said ends, bracket plates connected to the plugs to support the coil, and a ringlike woven primary disposed around a great circle periphery of the secondary at right angles to the axis 75 passing through the plug.

4. A transformer comprising a continuously wound secondary coil having the form of a sphere, the several convolutions of the coil being self-sustaining, and a continuously wound primary coil of ring-like configuration encircling said secondary coil.

5. A transformer comprising a continuously wound secondary coil having the form of a sphere, the several convolutions of the coil being self-sustaining, and a continuously wound primary coil of ring-like configuration supported directly upon and encircling said secondary coil.

ANTHONY P. HINSKY.
